JUG HANDLE

Norman A. Kelly, Wayne Township, Kosciusko County, Ind., assignor to Haskon, Inc., Warsaw, Ind., a corporation of Delaware

Filed Jan. 13, 1967, Ser. No. 5,404

Term of patent 14 years

(Cl. D58—5)

The broken line showing of a portion of a jug in FIG. 1 is for illustrative purposes only.

I claim:

The ornamental design for a jug handle, as shown and described.
